UNITED STATES PATENT OFFICE.

WALTER FARQUHAR LARKINS, OF LONDON, ENGLAND.

SIGNALING SYSTEM.

SPECIFICATION forming part of Letters Patent No. 558,820, dated April 21, 1896.

Application filed October 12, 1894. Serial No. 525,716. (No model.) Patented in England September 21, 1893, No. 17,778.

To all whom it may concern:

Be it known that I, WALTER FARQUHAR LARKINS, a subject of the Queen of Great Britain, and a resident of 104 Harley Street, 5 London, England, have invented certain new and useful Improvements in Signaling, with especial reference to the International Code of Signals, (patented in Great Britain, No. 17,778, September 21, 1893,) of which the following is a specification.

My invention consists in a system of signaling comprising two semaphore-arms only (having the important characteristics herein-after explained) for signaling by day the international alphabetical code, which for the purpose is divided into vertical columns and horizontal lines, so that the said distinctive semaphore-arms, when exhibited together and on opposite sides of a post or mast, may be 15 made to indicate by their position any letter, word, sentence, or character whatsoever in any code contained. Two semaphore-arms only are used, each of which has a distinctive character either as to color or design of its marking. Both arms are always used in combination and never singly. The arms are always exhibited on opposite sides of the mast, never both on the same side. The function of each arm is separate and distinct from that of the 20 other arm. The position of one arm indicates the number of line and the position of the other arm indicates the number of the column in which the designated letter or character is to be found. The value of one arm—viz., the 25 column-indicating arm—is the same on either side of the mast. The two arms can be made to designate eighteen different letters of a code with only six movements.

In the annexed drawings, Figure 1 represents a semaphore and code as employed according to my system, the line-arm *a* being in position to designate the second line on the left and the column-line *b* in position to designate the first column, the letter "C" being 30 thus signaled. Fig. 2 is a similar view with the semaphore-arms in position to signal the letter "H" in the sixth line and first column of the code. Fig. 3 represents the code-table as usually arranged in signal-books.

For the purposes of my improved system of day signaling I employ a semaphore compris-

ing two arms *a b*, Figs. 1 and 2, such as have been or are in use for semaphore or railway signals. These arms *a b* I may pivot to a mast *c* or I may otherwise exhibit them. On the 55 top of the mast projecting from the left side I fix a ball *d* or other object, but by preference a ball, to indicate to the observer the proper side of the mast from which to read off signals. The arms *a b* are fixed in pairs and 60 work on the same pivot *e* independently of each other, and three or four pairs (or more, if required) may be fitted on the same mast, one below the other, at convenient intervals of space in grooves or otherwise, or instead of 65 having three or four pairs of arms on one mast single pairs of arms may be fitted on two, three, or more masts placed in a row, allowing a convenient distance between the masts, provided the left-hand mast has the ball above 70 referred to fixed at the top.

The functions of the two arms are separate and distinct, and it is accordingly essential that they should differ in appearance in such manner as to insure as far as possible that the 75 one shall be clearly distinguishable from the other at a distance. One arm, *a*, is therefore preferably colored black, and the other arm, *b*, is black and white either in stripes or dots, as shown, or has other distinctive marking or 80 coloring.

The arms may be respectively elevated or lowered into the positions indicated by the dotted lines of Figs. 1 and 2, or into such positions as may be required—namely: position 85 1, upward at an angle of about forty-five degrees, not less; position 2, horizontal or at right angles to the mast; position 3, downward at an angle of about forty-five degrees, not less.

When no signaling is going on the arms are 90 not visible. Their use when at work will be found explained in the following remarks:

The international code of signals is, as at present in use, worked with eighteen flags, 95 and the signs employed to represent these symbols are eighteen letters of the alphabet, "B" to "W," (all vowels being omitted.) The table of flags in all signal-books is arranged in three columns of six letters in each column, as particularly shown in Fig. 3. It is 100 obvious that if I number the columns and

lines as indicated in Fig. 3 column 2, line 3, would give letter "L," or line 4, column 3, letter "T."

To carry out my method I take the table of 5 letters (or flags) and dividing it into two, I place one half (the first three upper lines) on the left and the other half (the lower three lines) on the right of the mast, as in Figs. 1 and 2. I name one of the arms, and by preference the plain black arm *a*, the "line-arm," because its function is to point to any one of the six lines right or left of the mast which contains the letter signaled or required to be signaled. The other arm, *b*, I call the 15 "column-arm," because its function is to indicate by its position—first, upward; second, horizontal, or third, downward on either side of the mast—the column in which to find the particular letter signaled—*i. e.*, the first, second, or third in the line pointed to by the other arm. Thus by hoisting any two arms simultaneously into their respective positions, as required, and always on opposite sides of the mast, any one of the letters in the 25 table can be indicated at once, and by similarly hoisting any two, three, or four pairs of arms it is possible by my method to signal with ease and rapidity any word, sentence, number, or communication whatsoever in any 30 code contained. Thus in Fig. 1 the line-arm is at the second or horizontal position, indicating the second line, and the column-arm is at the upward or first position, indicating the first column. The letter signaled is therefore "C."

In Fig. 2 the line-arm *a* occupies the sixth

position, or the third position on that side of the mast, and therefore indicates the sixth line in the table, Fig. 3, or the third line of the table on that side of the mast, and the 40 column-arm *b* is in the first position, indicating the first column. The letter signaled is therefore "H."

By reference to the numbered lines in Fig. 1, representing the positions to which the 45 arms *a* and *b* are to be turned, as required, it will be seen that the said arms used together may thus be made to readily designate and distinguish the eighteen different letters of the international code. 50

What I claim, and desire to secure by Letters Patent, is—

The herein-described means for signaling, consisting of two semaphore-arms, only, the said arms being distinctive in character and 55 arranged when in operation on opposite sides of a mast or support and in variable positions, the position of one arm being indicative of the number of line and the position of the other arm indicative of the number of 60 column in which is to be found the required letter or character of a code in which the letters or characters are arranged in horizontal lines and vertical columns, substantially as described. 65

In witness whereof I have hereto signed my name, in the presence of two subscribing witnesses, this 29th day of August, 1894.

WALTER FARQUHAR LARKINS.
